Patented Jan. 31, 1922.

INVENTOR,
W. H. McKissick;
BY *Howard D. Blaklee*,
ATTORNEY.

UNITED STATES PATENT OFFICE.

WILLIAM H. MCKISSICK, OF TULSA, OKLAHOMA.

TUBING DRAINER FOR WELL APPARATUS.

1,404,874.

Specification of Letters Patent. Patented Jan. 31, 1922.

Application filed October 15, 1919. Serial No. 330,699.

To all whom it may concern:

Be it known that I, WILLIAM H. MCKISSICK, a citizen of the United States, residing at Tulsa, in the county of Tulsa and State 5 of Oklahoma, have invented new and useful Improvements in Tubing Drainers for Well Apparatus, of which the following is a specification.

In the operation of deep wells the oil, 10 water or gas is ordinarily brought to the surface by means of a pump carried by a string of tubing through which the oil or fluid is conveyed from the bottom of the well to the surface of the ground, or the gas fused. 15 According to the standard practice the lower end of this string of tubing is provided with an upwardly opening check valve known as the "standing valve." This standing valve traps the oil or fluid in the string of tubing, 20 with the result that when it becomes necessary to pull the tubing from the well for the purpose of making some adjustments or repairs the oil or fluid which is trapped in the string of tubing by the standing valve is 25 lost. Ordinarily several barrels of oil are wasted in this manner every time the tubing string is withdrawn, and this entails a considerable loss. The object of this invention 30 is to provide a novel and effective means for opening this standing valve and permitting the oil trapped in the string of tubing to drain back into the well before the tubing is withdrawn, thereby saving the oil and facilitating the withdrawal of the tubing from the 35 well, since this trapped oil in the tubing adds materially to the weight thereof and makes the handling of the tubing more difficult.

Further objects of the invention are to provide a device for opening the standing valve 40 of a string of tubing which can be used with the standard oil well equipment without the necessity of any material changes therein, which is thoroughly dependable in its action, which can be actuated from the surface of 45 the well by a bodily movement of the string of tubing, and which has no complicated parts to break or get out of repair.

With these and other objects in view, the invention consists in certain novel combinations, arrangements and associations of the 50 parts, as will more fully appear as the description proceeds, the novel features thereof being pointed out in the appended claims.

For a full understanding of the invention 55 reference is to be had to the following de-

scription and accompanying drawings in which:

Figure 1 is a side elevation of the lower end of a string of tubing to which the device for opening the standing valve is applied, 60 said device being in the position assumed when lowering the string of tubing into the oil well, parts being broken away and shown in section;

Figure 2 is a similar view with the parts 65 in the position assumed after the device has been lowered into the well and preparatory to rotating the tubing to operate the device;

Figure 3 is a similar view showing the parts in the position assumed thereby after 70 the string of tubing has been rotated to actuate the device and lift the standing valve ball from its seat.

Fig. 4 is a view on an enlarged scale showing a detail of the device for opening the 75 standing valve.

Corresponding and like parts are referred to in the following description and in all of the views of the drawing by like reference characters.

Referring to the accompanying drawings which illustrate one possible embodiment of the invention, the numeral 1 designates the casing of the well, and 2 the lower end portion of a string of tubing formed of sections 85 which are detachably connected in the usual manner by the tubing collars 3. A standing valve 4 which is of the conventional construction is shown as fitted in the string of tubing at the lower end of one of the sections thereof, and the tubing below this valve may be perforated, as indicated at 5 to provide openings through which the oil or fluid in the well can enter the tubing. It will be under-

stood that a pump of any standard construction is intended to be fitted in the tubing above the standing valve 4 and that the fluid will be pumped to the surface of the well through the tubing. It is necessary at intervals of time to pull the tubing and withdraw 90 it from the well, and the object of the present invention is to provide a means for opening the standing valve and permitting the oil or fluid which has been trapped in the string of tubing to drain back into the well prepara-

100 tory to pulling the tubing, thereby avoiding the waste of perhaps several barrels of this oil or fluid.

A valve lifting stem 6 extends through the tubing length immediately below the stand-

ing valve 4 and the upper end of this stem is received within the lower end of the standing valve, while the lower end of the stem has a T-shaped head, being provided with 5 oppositely extending lateral arms 7 which project through angular slots 8 in the sides of the tubing. These slots 8 are formed in diametrically opposite sides of the tubing and each includes a vertical arm and an angularly disposed arm communicating with the lower end of the vertical arm. Ordinarily the lateral arm 7 of the T-head of the lifting stem drops by gravity into the lower ends of the inclined portions of the angular slots 8, and the stem is such a length that the upper end thereof is then slightly spaced from the bottom member of the standing valve.

Upper and lower collars 9 and 10 respectively, are loosely mounted upon this tubing length, said collars being connected by outwardly bowed spring arms 11 which are adapted to frictionally engage the inner walls of the well casing 1 to hold the collars against rotation within the well casing. The lower collar 10 is provided at opposite sides thereof with depending wings 12 which have inclined or cam edge portions adapted to engage projecting ends of the 30 T-shaped head 7 of the valve lifting stem 6 in a manner to be described.

When the string of tubing is being lowered into the well the frictional engagement of the spring arms 11 with the walls of the casing 35 1 will cause the friction device to slide upwardly on the tubing until the upper collar 9 engages one of the tubing collars 3, this position of the parts being clearly indicated by Figure 1. After the tubing has been 40 lowered to the desired depth in the well it is pulled upwardly a short distance and the wings 12 of the lower collar 10 brought into cooperative relation with the projecting ends of the T-shaped head 7 of the stem 6.

45 This can be insured by rotating the string of tubing in a direction required to operate the device while pulling upwardly thereon. The parts then assume the position shown in Figure 2 of the drawing. In order to operate the device and open the standing valve 4 it is now merely necessary to rotate the string of tubing in such a direction as to bring the projecting ends of the T-shaped head 7 of the valve lifting stem 6 into progressive engagement with the inclined edges 50 13 of the wings 12. It will be noted that the lower angular portions of the slots 8 in the tubing have an inclination which is reversely disposed with respect to the edges 13 of the

55 wings so that the inclined lower edges of the slots and the inclined edges 13 of the wings both have a cam action tending to lift the T-shaped head 7 as the string of tubing is rotated. In this connection it will be remembered that the collar 10 and wings 12

are held against rotation within the well casing 1 by means of the spring arms 11. The T-shaped head 7 of the valve lifting stem is thus rotated in the tubing and brought toward the vertical portions of the 70 slots 8. As the T-head 7 is rotated within the tubing it is lifted by the cam action of the wings 12 and inclined edge portions of the slots, thereby moving the stem 6 upwardly within the tubing and causing the 75 ball of the standing valve 4 to be raised from its seat, as indicated by Figure 3. Any oil or fluid which may have been trapped within the string of tubing above the standing valve can now drain back into the well, 80 thereby enabling the tubing to be withdrawn from the well and unjointed without wasting this oil or fluid. Should a further opening of the standing valve be desired a slight downward movement of the tubing after the 85 initial rotation thereof to trip the device would serve to move the T-head 7 upwardly in the vertical portions of the slots 8 and open the valve to a greater extent. If it is desired to close the standing valve without 90 removing the tubing from the well, this can be accomplished by rotating the string of tubing in an opposite direction and permitting the valve lifting stem 6 to drop back into inoperative position by the action of 95 gravity. This device can be used in connection with the standard oil well equipment now in general use and provides a most effective means for opening the standing valve when it is desired to drain the string 100 of tubing.

While I have illustrated and described one particular embodiment of my invention, it will be understood that I do not restrict myself to the exact details shown, since it 105 will be obvious that numerous modifications and changes can be made without departing in any manner from the spirit of the invention.

What I claim and desire to secure by Letters Patent is:

1. In a well apparatus, the combination, with a string of tubing, of a valve within said tubing; and means co-operating with said tubing and valve for opening or closing said valve incident upon rotation of said tubing, whereby the tubing may be drained; said means including a cam member; and a valve opening stem adapted to be actuated thereby. 115

2. In a well apparatus, the combination, with a string of tubing, of a valve within said tubing; and means co-operating with said tubing and valve for opening or closing said valve incident upon rotation of said tubing, whereby the tubing may be drained; said means including a valve opening stem, and a cam member; said cam member being so associated with the tubing as to be actuated by a bodily rotation of the tubing and 125 130

to move the stem into engagement with the valve to open the same.

3. In a well apparatus, the combination with a string of tubing and its standing valve, of a trip member rotatable upon the tubing, means for locking the trip member against rotation with the tubing, and a valve-unseating element arranged for rotation with the trip member to open the standing valve upon rotation of the string of tubing.

4. In a well apparatus, the combination with a casing and a string of tubing, including its standing valve, of a cam trip member rotatable on the tubing, means carried by the trip member for engaging the casing to hold the trip member against rotation, a valve opening stem within the tubing, and means actuated by the trip member upon rotation of the tubing to move the valve opening element into operative position.

5. In a well apparatus, the combination with a casing and a string of tubing, including its standing valve, said tubing being provided with a slot, a valve opening element arranged within the tubing and formed with an arm extending through the slot, a trip member rotatable on the tubing and formed with a cam portion adapted to engage the said arm to move the valve opening element into engagement with the standing valve, and means carried by the trip member for engaging the casing to lock the trip member against rotation and render the cam portion thereof operative when the tubing is rotated.

6. In a well apparatus, the combination with a casing and a string of tubing, including its standing valve, said tubing being formed with a slot having an angular portion, a valve operating element arranged within the tubing and formed with a lateral arm projecting through the slot, a ring rotatable with relation to the tubing and

formed with a cam portion adapted to cooperate with the angularly disposed slot to act upon the lateral arm and move the valve operating element longitudinally of the tubing into engagement with the valve, and means carried by the ring for engaging the casing to hold the ring against rotation when the tubing is rotated.

7. In a well apparatus, the combination with a casing and a string of tubing, including its standing valve, said tubing being formed with slots having angular portions, a valve opening stem arranged within the tubing and formed with a T portion of which the arms extend through the slots, a ring loose upon the tubing, means carried by the ring for engaging the casing to lock the ring against rotation, and cam means upon the ring for engagement with the projecting ends of the T portion of the valve opening stem to move the stem into engagement with the valve when the tubing is rotated.

8. In a well apparatus, the combination with a casing and a string of tubing, including its standing valve, said tubing having slots in the sides thereof, a valve opening stem arranged within the tubing and formed with a T portion of which the arms project through the slots of the tubing, upper and lower rings slidably and relatively rotatably mounted upon the tubing, spring arms connecting the rings and frictionally engaging the casing to lock the rings against rotation, and cam means carried by one of the rings for engaging the projecting arms of the T portion of the valve opening stem to move the same into operative position when the tubing is rotated.

In testimony whereof, I have signed my name to this specification in the presence of two subscribing witnesses.

WILLIAM H. McKISSICK.
